LAWN MOWER HOUSING

Clifford Brooks Stevens, Fox Point, Wis., assignor to
Outboard Marine Corporation, Waukegan, Ill., a
corporation of Delaware

Filed Apr. 27, 1962, Ser. No. 69,882

Term of patent 14 years

(Cl. D40—1)

FIGURE 1 is a perspective view showing the top, front, and one side of a first embodiment of a lawn mower housing incorporating my design;

FIGURE 2 is a perspective view showing the top, rear, and the other side of the lawn mower housing shown in FIGURE 1;

FIGURE 3 is a perspective view showing the bottom, front, and other side of the lawn mower housing shown in FIGURES 1 and 4;

FIGURE 4 is a perspective view showing the top, front, and one side of a second embodiment of a lawn mower housing incorporating my design;

FIGURE 5 is a perspective view showing the top, rear, and other side of the lawn mower housing shown in FIGURE 4;

FIGURE 6 is a perspective view showing the top, front, and one side of a third embodiment of a lawn mower housing incorporating my design;

FIGURE 7 is a perspective view showing the top, rear, and other side of the lawn mower housing shown in FIGURE 6;

FIGURE 8 is a perspective view showing the bottom,

rear, and said one side of the lawn mower housing shown in FIGURES 6 and 9; and

FIGURE 9 is a perspective view showing the top, front, and one side of a fourth embodiment of a lawn mower housing incorporating my design.

The broken line representation of a motor and wheels in FIGURE 1 is for the purpose of illustration only.

I claim:

The ornamental design for a lawn mower housing, as shown and described.
